ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DOOR-LOCKING MECHANISM FOR DUMP OR PLOW CARS.

1,205,157.

Specification of Letters Patent.

Patented Nov. 21, 1916.

Original application filed September 8, 1913, Serial No. 788,524. Divided and this application filed October 30, 1914. Serial No. 869,356.

To all whom it may concern:

Be it known that I, ARGYLE CAMPBELL, a citizen of the United States, residing in Chicago, in the county of Cook and State 5 of Illinois, have invented a new and useful Improvement in Door-Locking Mechanisms for Dump or Plow Cars, of which the following is a specification.

This invention relates in general to door 10 locking mechanisms for dump or plow cars and is a division of my earlier application Serial No. 788524, filed Sept. 8, 1913.

Dump or plow cars are frequently provided with side walls formed of doors pivoted along their top edges and hanging vertically downwardly when closed. These doors are adapted to swing outwardly when the car is being unloaded by the use of an unloading plow or in other manner. 15

20 The doors having their free edges adjacent the floor of the car, must be firmly secured in position when the car is loaded and must be readily releasable to permit unloading.

It is a principal object of this invention 25 to provide novel and improved means for securing the lower edges of these doors in position, such means being so constructed and arranged as to positively hold the doors rigidly in closed position and yet be easily 30 released to permit all or a part of the doors at one side of the car to open through the single operation of a single operating lever or member.

A further object of the invention is to 35 so arrange such mechanism that it will not project beyond the side edges of the car floor when the doors are free and will thereby be fully protected from damage by the falling load as it is discharged from 40 the car.

Other objects and advantages of the invention will be apparent as it is better understood from the following description when considered in connection with the 45 accompanying drawing illustrating a preferred embodiment thereof.

Referring to the drawings: Figure 1 is a side elevation of a portion of a car provided with a mechanism embodying my 50 present invention; Fig. 2 is a sectional view taken transversely of the car shown in Fig. 1 near one of its ends; and Fig. 3 is an enlarged detailed view taken sectionally through one of the loops with which the

doors are provided to engage the locking 55 mechanism, as will be later described.

In the embodiment of the invention shown on the drawing only a portion of the car is disclosed and the running-gear is entirely omitted, as it forms no part of 60 my present invention.

In the car body shown on the drawings each side of the car comprises two longitudinal top side members 12 arranged at right angles to each other and supported 65 at intervals with side stakes or supports 13. Between the side stakes and forming the body of the side wall of the car are doors 14 pivotally mounted along their top edges to the vertically disposed top members 12 70 by hinge butts 15, hinge members 16 and pivot pins 17 connecting the hinge members with the hinge butts.

The hinge members 16 are of heavy metal and extend clear across the width or height 75 of the door. Beyond the door these hinge members are extended and turned upon themselves to form cam shaped loops 18, as shown in Fig. 2. These loops are curved on their outer face beneath the floor 22 of the 80 car and are adapted to be engaged by locking loops 19 to secure the doors in closed position. The locking loops 18 are of U-shape form and each embraces at its ends a shaft or rod 19 of angular cross-section 85 so that turning of the rod 19 in its bearings will swing the U-shape members 18 vertically into and out of engagement with the loops of the hinge members 16, the outer portion of the U-shape members sliding up 90 the cam faces of the loops on the hinge members and drawing these members tightly against the side edges of the car floor to lock the doors in closed position. The shaft 19 is provided with an operating lever or 95 arm 20 disposed substantially in the plane of the U-shape members 18, and this shaft is mounted to turn freely in bearings 21 positioned beneath the floor 22 of the car, said bearings being secured to the side sill 100 girders 23. This arrangement permits both the lever arm 20 and the U-shape members 18 to be disposed downwardly out of the way while the car is unloading, the U-shape members being thus fully protected 105 from the falling load. The cam surfaces of the U-shape loops are in tight frictional engagement with the U-shape members when

the doors are locked, and to aid these cam surfaces in retaining the U-shape members in locking position against the action of the vibration of the train in movement, I provide a positive lock, consisting of a ratchet wheel 25 and a pawl or latch 24, the ratchet wheel being fast on the shaft and the pawl 24 pivoted to move freely on an appropriate part of the car. Loops of the downwardly extending hinge members 16 form convenient handles for lifting one of the car doors should it stick in use.

It will be manifest also that the locking loops 18 fixed to the shaft are under tension in the exercise of their holding function, and that such arrangement maintains the shaft itself under a pulling or tension strain while any strain is exerted upon the locking loops 18. This arrangement is believed to add materially to the strength of the construction.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. A plow car having side doors pivoted at their upper edges extending from end to end of the car, and mechanism for closing and locking said doors, said mechanism in-

cluding loops on the lower edges of said doors, a longitudinally extending shaft and members on said shaft adapted to engage said loops and cam the doors to closed position, substantially as specified. 40

2. A plow car having pivoted side doors extending from end to end of the car, and mechanism for locking said doors in closed position, said mechanism including depending loops fixed to the lower ends of the doors, each loop having an exterior cam surface, a longitudinally extending shaft and U-shaped members secured to said shaft, the number of said U-shaped members corresponding to the number of said loops and adapted to engage the latter and thereby cam the doors to closed position, substantially as specified. 45

3. A car of the character described having swinging side doors suspended by hinge members along their upper edges, side girders offset inwardly from the car sides forming angles with the floor of the car, and mechanism for closing and locking said side doors, said mechanism including longitudinally extending shafts located within said angles and loops formed integrally with the hinge members on the side doors by which the latter are pivoted. 50

Signed in the presence of two subscribing witnesses.

ARGYLE CAMPBELL.
